UNITED STATES PATENT OFFICE.

GEORGE W. EVERETT, OF NEW YORK, N. Y.

WEATHER-STRIP FOR WINDOWS, &c.

SPECIFICATION forming part of Letters Patent No. 349,877, dated September 28, 1886.

Application filed March 2, 1886. Serial No. 193,733. (No model.)

To all whom it may concern:

Be it known that I, GEORGE W. EVERETT, of the city, county, and State of New York, have invented a new and useful Improvement 5 in Weather-Strips for Windows, &c., of which the following is a full, clear, and exact description.

This invention, which is mainly intended to be applied to windows having sliding sashes, 10 and is designed to operate as a weather-strip thereto, differs essentially from weather strips as ordinarily constructed, inasmuch as the strip is not an exterior appendage, but is concealed within the sashes and parting-strips of 15 the window, whereby and by its peculiar construction many advantages are secured.

The invention consists in a flexible strip, made of rubber or its equivalent, secured to and arranged to project from the one part or 20 piece of the joint to be closed and entering at its free or projecting end within a flute, groove, or recess in the other part or piece of the joint, said parts or pieces being the parting-strips and sashes of the window, and meeting- 25 rails of the sashes, as hereinafter described.

Reference is to be had to the accompanying drawings, forming a part of this specification, in which similar letters of reference indicate corresponding parts in all the figures.

30 Figure 1 represents an inner face view of a window having upper and lower sashes with my invention applied. Fig. 2 is a horizontal section of the same in part on the line $\alpha\alpha$ in Fig. 1, the lower sash being raised; Fig. 3, a 35 vertical section in part upon the line yy in Fig. 1.

A indicates the frame of the window, B its upper sash, and C its lower sash, having panes or glasses $a\ a$. Both of these sashes are or 40 may be sliding ones.

D D are the parting-strips, and E E the stop-bars, either constructed of single pieces, as usual, or divided intermediately of their length and united by metal plates b , to facilitate the 45 removal of either sash without disturbing the other.

$d\ d$ are the meeting-rails of the sashes, of the usual counter-check construction.

The parting-strips D have saw-cuts made in 50 their sides throughout their length, shaped to hold the one edge of flexible rubber strips $e\ e$ within them. These strips when thus secured project beyond the sides of the parting-strips

throughout the length thereof, and when the sashes B C are fitted to their places are of sufficient width to curl or enter in a close but easy-fitting manner at their free edges within flutes or grooves $f\ f$ in the adjacent sides of the sashes throughout the length thereof and permit of the sashes freely moving up and down them. The meeting-rails $d\ d$ are similarly provided throughout their length on or in their adjacent faces, the one with a projecting rubber strip, e , which may be secured within a strip let into the sash, and the other with an angularly-shaped groove or recess, f , adapted to receive the free edge of the elastic strip f in an easy or curling manner within it, with capacity, when the sashes are being opened or closed, of working out and returning into said groove, but, as in the case of the flexible strips applied to the parting-strips, being concealed or under cover of the sashes when the latter are closed. Thus in both cases each rubber strip on the one part or piece of the joint to be closed enters in a concealed manner within a flute, groove, or recess in the other part or piece of the joint.

The improved weather-strip, as above described, not only serves to make a close joint for the exclusion of dust or wind and weather, but it presents no appreciable obstruction to the movement of the sashes up or down, and does not deface the window as most or all exterior weather strips do. It is protected, too, by its concealment within the sashes, from injury by the weather, and will consequently be more durable, nor is it necessary to remove it to put in the sash-cords.

Having thus fully described my invention, I claim as new and desire to secure by Letters Patent—

The combination, with the parting strip or strips D, of the attached elastic strip or strips e , arranged to project from the sides of the parting-strips, and the sash or sashes B C, provided with flutes, grooves, or elongated recesses f , adapted to receive under cover of the sashes in a close or closing manner the free edges of the elastic strips within them, essentially as shown and described.

GEORGE W. EVERETT.
